COAL MINING AND LOADING MACHINE

Original Filed June 4, 1917

Edmund C. Morgan

UNITED STATES PATENT OFFICE

EDMUND C. MORGAN, OF NEW YORK, N. Y.; OLIVE EUGENIE MORGAN EXECUTRIX OF
THE ESTATE OF SAID EDMUND C. MORGAN, DECEASED

COAL MINING AND LOADING MACHINE

Application filed June 4, 1917, Serial No. 172,651. Renewed April 6, 1927.

The object of my invention is to provide a simple and efficient machine for loading coal.

Referring to the drawing Fig. 1 is a side view of the entire machine. Fig. 2 is a top view of the same. Fig. 3 is an enlarged sectional view of the feeding mechanism taken partly on line 3—3, and partly on line 5—5, Fig. 2 in the direction indicated by the arrows on those lines. Fig. 4 is a sectional view 10 of a portion of the driving gearing for the upper chain cutter and the forward conveyor taken in line 4—4, Fig. 2. Fig. 5 is a sectional view taken on line 5—5, Fig. 2, in the direction indicated by the arrows, showing 15 a hydraulic breaker and pump for operating it. Fig. 6 is a sectional view showing extensible driving connection for the upper cutting chain as indicated by the arrow at 6 Fig. 1, where it is nearly all broken away.

Similar reference characters refer to similar parts throughout the several views.

Referring to Figures 1 and 2, the main frame 8 carries a conveyor frame 9 by means of the brackets 10 and 11; also mounted in 25 the main frame 8 is an electric motor 12, which drives all the mechanism of the machine by means of pinion 13 on the forward end of the motor shaft 14, and the pinion 15 at the rear end of the motor shaft. A vertical stationary shaft 16 is secured at its lower 30 end to the main frame 8 and at its upper end to the conveyor frame 9 and forms a pivot for the swinging frame 17. The swinging frame 17 is also further supported by the 35 segment of a gear 18' which is secured to the conveyor frame 9 and has its face concentric with the vertical shaft 16. The swinging frame 17 carries two chain kerf cutters, A and B, a breaking mechanism C, a conveyor 40 D, and feeding mechanism E, all of which are driven by the motor pinion 13 through the bevel gear 18, bevel gear 19 and sprocket wheel 20 which are connected together and loosely mounted on the stationary shaft 16 45 to revolve as an unitary structure.

The two chain kerf cutters are similar in construction to the kerf cutter shown in my Patent No. 550,283, issued Nov. 26, 1895. The lower kerf cutter is rigidly connected to the frame 17, and its chain is driven directly by 50 the sprocket wheel 20. The upper kerf cutter is vertically adjustably mounted on the frame 17 by means of two hollow posts 21 and 22 secured to the frame 17 into which two screw shafts 23 and 24 secured to the cutter frame are respectively arranged to slide. The cutter frame is raised, lowered and held in any desired position by threaded worm gear 25 mounted on screw shaft 23 and bearing 55 on top of the hollow post 21, and the threaded worm gear 26 mounted on screw shaft 24 and bearing on top of hollow post 22—a shaft 27, having its outer ends squared to fit a square socket crank, is mounted in bearings on the posts 21 and 22, and has keyed 60 to it two worms 28, 29 arranged to mesh respectively with worm gears 25 and 26.

The cutting chain of the upper kerf cutter is driven from bevel gear 19 through bevel pinion 30, shaft 31, carried in the frame 17, 70 bevel pinion 32 mounted on shaft 31, bevel gear 33 meshing with bevel pinion 32 and mounted on shaft 34 which is carried in frame 17, bevel pinion 35 mounted on shaft 34, bevel gear 36 meshing with bevel pinion 35 and mounted on vertical extensible shaft 37, 75 mounted at its lower portion in frame 17, and at its upper end in suitable bearings 38, 39 in the upper cutter, on which is sprocket wheel 40 keyed to the shaft 37 which meshes with 80 and drives the cutting chain. The portion of this driving train not clearly shown in Figs. 1 and 2, is shown in enlarged sectional view Fig. 4 which is taken on line 4—4, Fig. 2, looking in the direction indicated by the 85 arrows.

That portion of the extensible shaft 37 broken away as indicated by the arrow at 6 Fig. 1, is shown in enlarged section Fig. 6. The breaking mechanism C shown in posi- 90

tion in the machine in Fig. 2, is more clearly shown in Fig. 5. It is carried by the upper cutter frame and arranged to operate in the upper kerf. It consists of the hydraulic cylinder 41 with its piston 42. The pump 43 comprises a piston 44 which is driven by an eccentric 45 keyed to the shaft 37. The eccentric 45 is connected to an eccentric strap 46 which in turn is connected to the piston 44. The pump is supported on the bearing 38 by means of a yoke 47 which is mounted on the upper part of said bearing 38 so as to have a slight turning movement. This yoke 47 is rigidly connected to the cylinder of the pump 43. The water supply is carried in the reservoir 48 which is cast integral with the pump cylinder. A passageway 49 with a valve 50 of usual construction connects the inside of the reservoir with the inside of the pump cylinder. A pipe 51 connects the pump with the breaker cylinder 41. This pipe is rigidly connected but owing to the length it would have in practice, it will flexibly yield to a considerable extent so as to permit of the necessary up and down movement of the breaker cylinder. A pipe 52 extends from the pipe 51 to the reservoir. At the junction of the pipes a valve 53 is provided so as to enable the operator at will to make connection between the breaking cylinder and pump or between breaker cylinder and reservoir. A check valve 54 of usual construction is provided at the end of the pump cylinder 43. The breaker cylinder 41 at its outer end, shown clearly in Fig. 2, is supported in the cutter frame by means of a rod 55 attached to the cutter frame, the cylinder being loosely connected to the rod by means of two straps 56, 57 which permits of up and down movement and also sliding movement of the breaker cylinder. A spiral spring 58 is placed on the rod 55 and abuts against the strap 57 at one end, and against a nut 59 at its other end. The rod 55 is threaded a considerable distance so that by means of the nut 59, any tension desired may be put on the spring.

It will be noted that by means of the pivoted connection formed by the yoke 47, on the bearing 38, swinging movement of the whole breaker apparatus is provided which will permit the breaker to stand still when doing its work while the cutter frame continues to move forward.

The conveyor mechanism indicated as a whole by the letter D carried in the swinging frame 17, receives the coal that is detached by the action of the kerf cutters and breaker, and delivers it to the hopper of the conveyor frame 9. The discharge end of the conveyor D registers with the circular lip of the hopper at any position of the travel of the swinging frame 17. The upper portion 60, of the conveyor D, is hinged at 61 so as to permit it to swing up if it strikes the

angular portion of the conveyor frame 9. That portion of the conveyor frame 9 which may be seen in plan in Fig. 2 between the forward hopper and the deep storage hopper below the U-shaped frame 98, constitutes an upwardly inclined chute for the scraper conveyor which comprises spaced-apart cross-flights movable along a stationary bed plate. This bed plate forms the bottom of the chute, the upper edges of which are located in position to be engaged by the upper portion 60 of the conveyor D. The moving portion of the conveyor D is of the upright endless chain type, consisting of two chains with scraper bars between. The chains at the receiving and discharging ends of the conveyor run over rollers and are driven by the sprockets 62 and 63, Fig. 4, which mesh with the lower runs of the chains. These sprockets are keyed to the shaft 64 which has suitable bearings in the conveyor frame 65. Power to drive the shaft 64 is derived from the shaft 34 by means of spur gear 66 keyed to the shaft 34 and spur gear 67 loosely mounted on shaft 64. The spur gear 67 has clutch jaws arranged to engage with the clutch 68 mounted on the shaft 64 and provided with a feather to drive it. The clutch 68 is thrown in and out of engagement with the spur gear 67 by means of a rod 70 of usual construction.

The swinging frame 17 is given its movement around its pivot in both directions by the feeding mechanism E shown in Figs. 1 and 2 but more clearly by the enlarged Fig. 3. Two speeds are provided by this feed mechanism.

Referring to Fig. 3 spur pinion 71, and internal gear 72 are loosely mounted on the upright shaft 37. They are provided with clutch jaws arranged to engage with the clutch 73 which is slidably mounted on the shaft 37, and provided with the usual feather to drive it. The clutch is controlled by the lever 74. A shaft 75 is mounted in suitable bearings in the frame 17, and has rigidly secured to it a pinion 76 meshing with internal gear 72, a spur gear 77, meshing with spur pinion 71, and a worm 78. The worm 78 meshes with worm gear 79, which is keyed to the shaft 80 mounted in suitable bearings in the frame 17. A worm 81 is keyed to the shaft 80, and meshes with the segmental gear 18' rigidly attached to the conveyor frame 9. This segmental gear is more clearly shown in Figs. 1 and 2.

The moving portion of the conveyor contained in the conveyor frame 9 is of the upright endless chain type, and is practically identical in construction to the moving part of the conveyor D except that the shaft 82 which corresponds to shaft 64 of the conveyor D is driven by the bevel pinion 83 and bevel gear 84 in place of the spur gears 66 and 67 respectively of the conveyor D, shown

in Fig. 4. The bevel pinion 83 and bevel gear 84 are shown in dotted lines in Figs. 1 and 2. The bevel pinion 83 is keyed to the shaft 85 which is carried in bearings 86, 87 in the conveyor frame 9 and bearing 88 in the main frame 81. The shaft 85 is driven from the electric motor by means of bevel gear 89 keyed to the shaft and bevel pinion 15, keyed to the motor shaft.

10 It is desirable to tilt the machine to adjust the position of the kerf cutters. I provide for this by two screw jacks 91 and 92 secured to the main frame 8. The machine is held in adjusted position by the two roof jacks 93 and 94.

15 From the above it will be seen that 8 designates the main frame on which is mounted the main conveyer 9 in fixed relation thereto. D designates a swinging supplemental conveyer 20 pivotally connected to the forward end of the main frame 8 and comprising an endless traveling conveyer, as shown in Figs. 1 and 2. The forward end of this endless traveling conveyer which is mounted on the 25 swinging supplemental frame 17, has its forward portion adapted to occupy an approximately horizontal position with its rear portion adapted to deliver material to the main conveyer 9 in the various angular positions of 30 the supplemental conveyer D relative to the main frame 8. The supplemental frame 17 is pivotally connected to the main frame 8 below the forward end of the main conveyer 9. Obviously the supplemental frame 17 has 35 a range of swinging movement relatively to the main frame of 180° or more which is evident from the extent of the worm gear 18 shown in Figs. 1 and 2. The supplemental conveyer D is in position to deliver material 40 to the main conveyer throughout the swinging range of movement of the former. Furthermore, although the motor 12 is mounted on the main frame 8, the power transmission gearing shown is adapted to operate the supplemental conveyer in the various angular 45 positions thereof relative to the main frame. It will also be seen by referring to Fig. 1 that the supplemental frame 17 is pivotally connected to the main frame in a relatively low 50 position adjacent the surface on which the main frame is adapted to rest, the connection being such that delivery communication with the main conveyer 9 is maintained throughout a wide angular movement of the supplemental frame 17 relatively to the main frame 8. This delivery communication is assured by the hopper shown in Figs. 1 and 2 at the forward and lower end of the main conveyer 9. By providing the pivotal connection 55 between the supplemental frame 17 and the main frame 8 below the hopper of the conveyer 9 the space above this hopper is maintained free and unobstructed so that the conveyer D can deliver material to the conveyer 9 throughout a wide angular swinging move-

ment of the supplemental frame 17 relatively to the main frame 8. It is evident that the range of swinging movement is 180° or more because when the conveyer 60 swings more than 90° from the position shown in Fig. 2 the upper section 60 of the conveyer D will engage the inclined side of the chute of the conveyer 9 and permit pivotal movement at 61 of the conveyer section 60.

An additional swinging supplemental conveyer F is mounted at the rear portion of the main frame 8 to swing laterally on an upright axis through an arc of 180° or more while delivery communication is maintained between the main conveyer 9 and the deep storage hopper at the forward end of the conveyer F, as shown in Figs. 1 and 2. It will thus be seen that the main conveyer 9 has a forward receiving portion in a relatively low position and a rear portion inclined upwardly toward the rear. The rear supplemental conveyer F is pivotally connected at 95 and 96 to the lower and upper rear end portions of the main frame 8 to swing on an upright axis through 180° or more. The pivotal connections 95 and 96 are spaced apart vertically and respectively located above and below the forward end of the conveyer F to provide a free and unobstructed receiving space above the forward end of the conveyer F, the latter being at the bottom of the deep storage hopper in a relatively low position and inclined upwardly and rearwardly toward delivery position at the rear end of the loading machine. This deep storage hopper surrounds the receiving space for directing material from the main conveyer 9 onto the conveyer F throughout the range of movement of the latter relatively to the main conveyer 9. By making the frame 98 U-shaped and extending it horizontally and rearwardly therefrom a free and unobstructed space is provided for delivery of material from the main conveyer 9 into the deep hopper. The upper pivotal connection at 96 supports the overhanging weight of the rear portion of the swinging conveyer F while permitting swinging movement of the latter on the upright axis extending through these pivotal connections.

The coal is received by the conveyor 9 and loaded into the mine cars by a swinging conveyor referred to as a whole by letter F, Figs. 1 and 2. It is pivotally supported by the main frame 8 and the conveyor frame 9, and arranged to swing through an arc of more than 180 degrees. A stud 95, resting in a suitable bearing in main frame 8, forms the pivotal support in the main frame 8, and a pin 96, connecting the T-shaped frame 97, attached to the swinging conveyor frame, to the loop frame 98, attached to the conveyor frame 9, forms the support on the conveyor frame 9. The swinging frame may be rigidly held in any position of its travel by means of a

brake consisting of a screw shaft 99, and a hand wheel nut 100, supported in the bracket 11.

The conveying mechanism of the swinging conveyor F, is the same construction as described for conveyor 9, the bevel pinion 101, bevel gear 102 and shaft 103 corresponding respectively to 83, 84 and 85 for conveyor 9. The shaft 103 of conveyor F is driven from shaft 85 by means of drive chains 104 and 105. These chains operate on sprockets as follows: Sprocket 106 which drives chain 105 is loosely mounted on shaft 85, and has driving connection with shaft 85 through clutch 107, slidably mounted on, and driven by shaft 85 by means of a suitable feather. Sprocket 108, loosely mounted on the stud 95, is driven by the drive chain 105. Sprocket 109, which is loosely mounted on stud 95, but rigidly connected to sprocket 108, drives chain 104. Sprocket 110 keyed to the shaft 103 is driven by chain 104.

It will be noted that as sprockets 108 and 109 are concentric with the pivot of conveyor F, the driving connection will be maintained at any position of the swing of the conveyor F. It should be noted that when the cutting mechanism and the breaker are entirely removed the remaining mechanism is a loading machine which may be used to gather material from both sides of and in advance of the forward portion of the main conveyer 9 while the supporting frame 8 remains stationary. The hopper at the forward end of the main conveyer 9 is concentric with the vertical shaft 16 so that the line of draft of the supplemental conveyer always remains radial relatively to the center of the hopper. Although the supplemental conveyer may be moved from one side of the hopper arcuately to the other side, the supplemental conveyer always remains in delivery communication with the main conveyer. In the same manner the line of draft of the main conveyer 9 extends toward the vertical axis of the swinging conveyer F. Throughout the various swinging angular positions of the conveyer F the main conveyer always remains in delivery communication with the loading conveyer. Each of the conveyers is preferably of the scraper type so as to minimize the width of the machine for transportation along a mine track and around sharp turns in a mine. It can be seen that although the conveyer is elongated when in operation the conveyers have relative turning movements on the axes at 16 and 96. The gathering conveyer D can swing through an arc of over 180° independently of the arcuate swinging movement of the loading conveyer F through an angle of over 180°. The motor 12 is located beneath the main conveyer and the driving mechanism to which it is connected is very compact notwithstanding the fact that it drives the gathering conveyer as well

as swings it and also drives the main conveyer and the loading conveyer. The deep storage hopper for the loading conveyer enables loading to be interrupted when desired by releasing the clutch 107, without discontinuing the operation of the gathering conveyer and the main conveyer 9. Also when desired the clutch 68 may be released to stop the operation of the gathering conveyer. The clutch 73 when released will stop the arcuate gathering movement of the gathering conveyer. When the cutting mechanism and the breaking down mechanism illustrated in the accompanying drawings are omitted the loading apparatus which remains is particularly adapted for use in coal mines to gather and load coal which has been broken down by blasting or otherwise from the face of the coal vein.

In my co-pending application, Serial No. 202,825, filed November 19, 1917, for apparatus for mining and unloading coal, I have shown and claimed the mining mechanism of the type herein disclosed and also such mining mechanism combined with the type of loading apparatus herein disclosed, the principal features common to said application and the present application are the floor kerf-cutter, the upper kerf-cutter adjustable in elevation, breaking-down mechanism within the periphery of the upper kerf-cutter, and also the forward endless conveyer in position to receive the broken down material and convey it to an intermediate conveyer to which the forward conveyer is pivotally connected, said intermediate conveyer delivering the material to the storage hopper which is provided with a loading conveyer, said storage hopper being provided also with pivotal connections above and below, whereby a floor kerf is cut as the most forward frame is swung in an arc together with the forward conveyer and at the same time an upper kerf is cut at an opposite inclination while the material is broken down by the breaking device and continuously carried back by the three conveyers serially arranged and successively delivering the material from one to the other, and the rearmost conveyer delivering the material into a mine car to which the rear conveyer is swung from the pivotal connections above and below the hopper.

Obviously those skilled in the art may make various changes in the details and arrangements of parts without departing from the spirit and scope of my invention as defined by the claims hereto appended, and I wish, therefore, not to be restricted to the precise construction herein disclosed.

Having shown and described an operative form of my invention, I claim:

1. In loading apparatus, the combination with a main frame adapted to rest on the floor of a mine chamber, of a main conveyer mounted on said main frame in fixed rela-

- tion thereto, a vertical shaft mounted on the forward end of said main frame and extending upwardly between the lower forward end of said main frame and the lower side of said main conveyer in a position adjacent the floor of the mine chamber leaving the forward end of said conveyer free and unobstructed on its upper side, a swinging supplemental frame connected to said vertical shaft for pivotal movement laterally relatively to said main frame over the floor of the mine chamber in advance of said main frame, a supplemental conveyer mounted on said supplemental frame for delivery communication to said main conveyer throughout the range of lateral movement of said supplemental frame relatively to said main frame, a motor mounted on said main frame back of said vertical shaft, and power transmission gearing between said motor and said supplemental frame for driving said supplemental conveyer and for swinging said supplemental frame together with said supplemental conveyer laterally relatively to said main frame while the forward receiving end of said supplemental conveyer occupies a position adjacent the floor of the mine chamber and the rear end of said supplemental conveyer remains in delivery communication with the forward end of said main conveyer.
2. In loading apparatus, the combination with a main frame, of a main conveyer mounted thereon, a motor mounted on said main frame, driving connections comprising a vertical shaft extending between said motor and said main conveyer, a swinging supplemental conveyer mounted on said main frame for pivotal movement relatively thereto on an upright axis, and driving means adapted to be connected at will between said vertical shaft and said supplemental conveyer to effect the driving of the latter at its various lateral positions relative to said main frame.
3. In loading apparatus, the combination with a main frame, of a main conveyer mounted thereon, a rear supplemental frame mounted on said main frame to swing on an upright axis relatively thereto, a supplemental conveyer mounted on said supplemental frame to extend rearwardly to a mine car, a motor on said main frame, and driving connections comprising a double sprocket with its axis concentric with the aforesaid upright axis, said driving connections extending from the motor to said axis and thence to the supplemental conveyer to drive the latter in its various lateral positions relative to said main frame.
4. In loading apparatus, the combination with a main frame, of a supplemental frame mounted to swing on an upright axis relatively to said main frame, a supplemental conveyer mounted on said supplemental
- frame to deliver material to a predetermined location relative to said main frame, a driving sprocket concentric with said upright axis, a motor on said main frame, driving mechanism between said motor and said conveyer and comprising a sprocket chain connected to said driving sprocket to effect the driving of said supplemental conveyer in the various angular positions of the latter, a worm gear secured to said main frame concentric to said upright axis, and auxiliary driving connections associated with said first-named driving connections for connection to said worm gear to effect the swinging of said supplemental frame together with said conveyer while the latter is being driven.
5. In loading apparatus, the combination with a main frame, of a main conveyer mounted thereon, a chute for said main conveyer, and a supplemental conveyer swingable laterally on an upright axis on said main frame and comprising a pivoted section in delivery communication with said main conveyer and adapted to swing upwardly when engaging one of the sides of said chute to maintain such delivery communication.
6. In loading apparatus, the combination with a main frame, of a main conveyer mounted thereon, a sectional supplemental conveyer mounted for lateral swinging movement on an upright axis on said main frame while maintaining delivery communication with said main conveyer in the various angular positions of said supplemental conveyer relative to said main frame, said supplemental conveyer comprising a delivery section pivoted on an approximately horizontal axis to swing upwardly when engaging said main frame upon movement to lateral positions, and means for driving said conveyers.
7. In loading apparatus, the combination with a main frame, of a main conveyer mounted thereon, a hopper at the forward end of said conveyer, an inclined chute extending upwardly from said hopper, a supplemental frame mounted on said main frame to swing on an upright axis, a supplemental conveyer mounted on said supplemental frame and comprising a section pivoted on an approximately horizontal axis to permit tilting of said section when moved laterally into engagement with one side or the other of said chute adjacent said hopper, and means for driving said conveyers.
8. In loading apparatus, the combination with a main frame, of a main conveyer mounted thereon, a swinging supplemental conveyer pivotally connected to said main frame for swinging movement relatively thereto on an upright axis while maintained in delivery communication with said main conveyer from a position at right angles to the longitudinal length of the machine at one

side thereof to a position at right angles to such longitudinal length at the other side thereof, means for maintaining delivery communication between said conveyers throughout the range of lateral swinging movement of said supplemental conveyer, means for driving said supplemental conveyer, and mechanism comprising a stationary gear concentric with the pivotal axis of swinging movement of the supplemental conveyer for swinging the latter to its various angular positions relative to said main conveyer.
